UNITED STATES PATENT OFFICE.

THOMAS BENFIELD, OF NEWARK, NEW JERSEY.

DESIGN FOR A WATCH-CASE.

SPECIFICATION forming part of Design No. 21,482, dated April 19, 1892.

Application filed March 17, 1892. Serial No. 425,365. Term of patent 7 years.

To all whom it may concern:

Be it known that I, THOMAS BENFIELD, a subject of Her Majesty the Queen of Great Britain, residing at Newark, in the county of Essex and State of New Jersey, have invented and produced a new and original Design for Watch-Cases, of which the following is a specification, reference being had to the accompanying drawings, forming part thereof.

Figure 1 is a plan view of a watch-case, showing my new design. Fig. 2 is a sectional view taken on the line X X of Fig. 1.

As shown in the drawings, the leading or material feature of my design consists of a series of ribs A and grooves or corrugations B, disposed or arranged as shown in Fig. 1, the said ribs A being convex in cross-section and the grooves or corrugations B concave, as shown in Fig. 2. The ribs A are intersected

by the band of corrugations B, running from one end of the case to the other and formed of compound curves in their length, as shown. The center of the case is left plain, as shown at C. The several portions may, if it is manifest, be engraved, chased, or otherwise ornamented, as desired.

It is apparent that this design is also applicable to lockets and other similar articles.

Having described my invention, what I claim as new, and desire to secure by Letters Patent, is—

The design for a watch-case, as herein shown and described.

THOMAS BENFIELD.

Witnesses:

GEORGE COOK,
WILLIAM GOEBEL.
